Primary Examiner — Holly H Bayham*Assistant Examiner* — Rashida C. Walshon(74) *Attorney, Agent, or Firm* — Dinsmore & Shohl LLP; Toni-Junell Herbert; Therese M. Finan(57) **CLAIM**

The ornamental design for a protective spat for cleated or spiked sports shoes, as shown and described.

DESCRIPTION

FIG. 1 is a bottom perspective view of a protective spat for cleat or spiked sports shoes shown in use on an unclaimed shoe;

FIG. 2 is a top plan view of the design of FIG. 1 in use on an unclaimed shoe; and,

FIG. 3 is a left side elevational view of the design of FIG. 1 shown on an unclaimed shoe.

The broken lines forming the shoe inserted in the protective spat represent unclaimed environment. The broken lines immediately adjacent to the solid-line portions of the protective spat define the bounds of the claimed design form no part thereof.
